INNER WRAP PAPER HOLDER

Roy D. Shaw, Elsinore, Calif.

Application October 10, 1932. Serial No. 637,162

1 Claim. (Cl. 312—62)

The invention relates to a paper holder and more especially to an inner wrap waxed paper holder and dispenser.

The primary object of the invention is the provision of a holder of this character, wherein sheets of waxed paper may be conveniently held so that the same can be dispensed for use as an inner wrap for meats or other perishable merchandise, the sheets being confined in a novel manner and are readily accessible for single delivery in the use thereof.

Another object of the invention is the provision of a holder of this character, wherein the construction thereof is such that it may be hung upon a stall, meat block, counter or other support and when not in use will be out of the way, yet the same can be swung to a position for the dispensing singly of inner wrap waxed sheet paper ordinarily employed in the wrapping of meats or other merchandise, the sheets of paper being held conveniently ready for use and is advantageous to butchers or the like.

A further object of the invention is the provision of a holder of this character which is extremely simple in construction, thoroughly reliable and efficient in its purpose, strong, durable, readily and easily manipulated, and inexpensive to manufacture.

With these and other objects in view, the invention consists in the features of construction, combination and arrangement of parts as will be hereinafter more fully described in detail, illustrated in the accompanying drawing, which discloses the preferred embodiment of the invention, and pointed out in the claim hereunto appended.

In the accompanying drawing:

Figure 1 is a vertical sectional view through a support showing the holder constructed in accordance with the invention applied thereto and in normal position.

Figure 2 is a view similar to Figure 1 showing the holder adjusted for the removal singly of sheets of waxed paper therefrom during the merchandise of meats or other perishable merchandise.

Figure 3 is a sectional view on the line 3—3 of Figure 1 looking in the direction of the arrows.

Figure 4 is a sectional view on the line 4—4 of Figure 1 looking in the direction of the arrows.

Figure 5 is a sectional view on the line 5—5 of Figure 1 looking in the direction of the arrows.

Similar reference characters indicate corre-

sponding parts throughout the several views in the drawing.

Referring to the drawing in detail, A designates generally a portion of an upright constituting a support to which is applied the holder 60 constituting the present invention and herein-after fully described.

The holder comprises a plate-like base 10 preferably made from sheet metal cut and bent at its lower corners to provide outstanding pivot 65 ears 11 for the connection therewith of a swinging body 12, the latter being made from sheet metal and is bent to form a tray having the sides 13 and end 14 respectively, the opposite end being open and this tray is adapted to accommodate a stack of waxed sheet paper 15 as is clearly shown in Figure 2 of the drawing.

The sides 13 of the body 12 next to the end 14 thereof have projecting laterally therefrom pivot studs 16, these being journaled in the ears 75 11 so that the body can be swung upwardly and inwardly against the base 10 or pulled outwardly and downwardly for access to the paper 15 contained therein. The sheets of paper 15 are extracted or pulled outwardly from the body 12 80 through the open end 17 thereof.

Working against the stack of paper 15 is a follower plate 18 which is carried upon a spring arm 19, the same being fixed to or integrally formed with the end 14 of the body 12 at a 85 medial point thereof, the arm 19 being fitted with a spring finger 20 which plays against the plate 18 and holds the same flat against the stack of paper 15. The uppermost sheet of the stack 15 is readily removed by pulling the same 90 outwardly from the open end 17 of the body 12 on the lowering thereof to a dispensing position as shown in Figure 2 of the drawing, the normal position of the body 12 being shown in 95 Figure 1 of the drawing.

Formed on the base 10 at its opposite side edges near the uppermost portion thereof are spring finger-like keepers or latch members 21, each having an aperture 22 therein to accommodate a lug 23 formed on and projected outwardly from each side 13 of the body 12. These lugs on the swinging of the body 12 upwardly and inwardly against the base 10 will snap into the openings 22 in the members 21 which latter will latch the body 12 in its raised normal position so that the body will be out of the way when not in use for the dispensing of the sheets of paper 15 therefrom as should be clearly obvious.

The members 21 are formed with outwardly 110

curled free ends 24 to permit the riding of the lugs 23 into the openings 22 in said members 21 for the latching of the door 12 in raised position.

The follower plate 18 sustains the sheets of paper 15 of the stack compact and smooth in their superimposed relation in the stack.

The lugs 23 are positioned on the sides 13 of the body 12 for positive engagement with the members 21 which as previously stated latch the body 12 in its raised normal position.

What is claimed is:

A holder of the character described comprising a plate-like base formed from a single sheet of material bent at its lower corners to provide 15 outstanding pivot ears, a swinging body made from a single piece of material bent to form a

tray having sides and an end with the opposite end open, pivot studs projecting laterally from the sides of the swinging body and journaled in the ears for the swinging upwardly and inwardly of said body against the base, a follower plate carried within the swinging body, a spring arm made fast to the follower plate at one end and to the end of the body at its opposite end, a spring finger engaged with the spring arm and having a free end playing against the follower plate remote from the point of connection of the arm therewith, and spring finger-like keepers carried by the base and engageable with the sides of the body to hold the same normally closed against the said base. 90
